ABSTRACT OF THE DISCLOSURE

A single plunger, distributor type fuel injection pump, the improvement comprising means for filling the fuel distribution chamber during the entire downstroke of the pump plunger thereby preventing insufficient filling and cavitation erosion, especially at high engine speed, said means also preventing engine reversal; said means comprising an arrangement of supplementary ports in the plunger and complementing supplementary conduits in the pump hydraulic head to provide communication of the fuel distribution chamber with the fuel supply during the entire plunger downstroke.

The present invention relates to fuel injection pumps of the single plunger, distributor type such as that shown in U.S. Patent 2,518,473, issued Aug. 15, 1950, and assigned with the present application to a common assignee. In this type of pump, a reciprocating and rotating plunger pumps fuel from a fuel distribution chamber sequentially to the cylinders of the fuel injection engine on which it is mounted, each stroke of the plunger supplying an injection of fuel to an engine cylinder by means of a fuel injection nozzle. Fuel is supplied to the distribution chamber by a fuel supply pump, the fuel entering the chamber through supply passages which are fully open to the chamber only at the bottom of the plunger stroke. The amount of fuel pumped to the engine is controlled by means of an axial bore in the plunger which, in conjunction with radial spill ports, connects the fuel distribution chamber with a sump in which fuel is maintained at the fuel supply pressure. An adjustably positioned control sleeve on the plunger in the sump covers the spill ports during the pumping portion of the plunger stroke. When the spill ports clear the sleeve, the fuel distribution chamber pressure is reduced to the supply pressure, causing a check valve to close and thus terminating the fuel injection.

Difficulties have been experienced with this type of pump at high speed in maintaining the full discharge capacity of the pump. This is due to the failure of the fuel distribution chamber to fill with the necessary volume of fuel, even at increased fuel supply pressures. A further problem with this type of pump has resulted from the vacuum condition caused during the return stroke of the plunger after the spill ports have been reclosed and before the fuel supply passages have been opened, the chamber pressure during this period dropping below the vapor pressure of the fuel. The repeated collapse of the vacuum and transformation of the fuel from the vapor to the liquid phase causes cavitation erosion of the fuel supply ports and fuel distribution chamber. A further difficulty with the conventional pump is the possibility of reverse engine operation, for example following a false start, which can result in costly damage to the engine.

To correct the above difficulties, the present invention comprises the improvement of supplementary filling means for filling the fuel distribution chamber during the entire downstroke of the plunger. The supplemental filling means includes supplementary ports in the plunger and complementing supplementary conduits in the hydraulic head plunger bore communicating with the fuel supply.

2

The supplementary plunger ports and hydraulic head conduits are so arranged as to provide communication between the fuel distribution chamber and the fuel supply sump during the entire downstroke of the plunger. In addition, should the engine attempt to operate in reverse, the supplemental ports and conduits communicate during the compression stroke of the plunger thereby preventing the compression of fuel in the fuel distribution chamber and effectively preventing reverse engine operation.

In view of the above, it is a first object of the present invention to improve the fuel filling efficiency of the fuel distribution chamber of a single plunger, distributor type fuel injection pump by means of complementing supplementary ports in the plunger and conduits in the hydraulic head to provide communication of the chamber with the fuel supply during the downstroke of the plunger in addition to the fuel inflow through the regular fuel inlet ports.

A further object of the invention is to provide an improved fuel filling means as described operable during the entire downward stroke of the plunger to prevent fuel vaporization and the resultant cavitation damage.

Another object of the invention is to provide fuel filling means as described which provides an efficient fuel distribution chamber filling even at high engine speeds with a normal fuel supply pressure.

A still further object of the invention is to provide supplementary fuel filling means as described which will permit normal operation of the engine in its prescribed rotational direction but which will prevent the engine from running in the reverse direction.

Additional objects and advantages of the invention will be more readily apparent from the following detailed description of an embodiment thereof when taken together with the accompanying drawings, in which:

FIG. 1 is a partial sectional view taken through a fuel fuel injection pump embodying the present invention and showing the pump plunger in the bottom dead center position;

FIG. 2 is a sectional view taken along line 2—2 of FIG. 1;

FIG. 3 is a partial view taken as in FIG. 1 showing the portion of the pump hydraulic head surrounding the upper end of the plunger at the bottom dead center plunger position;

FIG. 4 is a sectional view taken along line 4—4 of FIG. 3 showing the supplementary plunger ports and their relation to the supplemental conduits in the hydraulic head at the plunger bottom read center position;

FIG. 5 is a view similar to FIG. 3 showing the plunger at the top dead center position;

FIG. 6 is a sectional view taken along line 6—6 of FIG. 5 and showing as in FIG. 4 the relationship of the supplemental ports and conduits;

FIG. 7 is a view similar to FIGS. 3 and 5 showing the plunger part way through the plunger downward stroke just before the opening of the main fuel supply passages;

FIG. 8 is a sectional view taken along line 8—8 of FIG. 7 and showing as in FIGS. 4 and 6 the relationship of the supplemental ports and conduits; and

FIG. 9 is a graph relating the engine rotation to the plunger movement through its cycle of operation and indicating the sequence of opening and closing of the various fuel filling means.

Referring to the drawings, and particularly FIGS. 1 and 2 therefore, a fuel injection pump 10 of the general type illustrated in the above-mentioned Patent 2,518,473, is shown in part including a hydraulic pump head 12 mounted on the main pump housing 14. The hydraulic pump head 12 includes a central vertical bore 16 within which a plunger 18 is slidably disposed, the plunger in conjunction with the threaded bore plug 20 defining a

fuel distribution chamber 22 in the upper end of the bore. The plunger passes through a sump or spill chamber 24 in the lower part of the hydraulic head and is rotatably and reciprocally driven for delivering fuel to cylinders of an internal combustion engine (not shown) in a manner to be presently described.

The pump is driven by the engine by means of the cam-shaft 26 which is suitably journaled in the main housing 14. A cam 28 on the cam-shaft having a plurality of cam lobes 30 coacts with roller 32 of tappet 34, and in conjunction with helical return springs 36 and 38 effects a reciprocating vertical stroke of the plunger. Rotation of the plunger is effected by means of a vertical quill shaft (not shown) geared to the cam-shaft and having a gear at the upper end thereof meshing with the sliding gear 40 on the plunger. The rotation of the cam-shaft 26 thus causes both a reciprocation and rotation of the plunger resulting in the cyclical plunger movement graphically illustrated in FIG. 9.

The hydraulic pump head 12 includes fuel inlet ports 42 and 44 on opposite sides thereof to which fuel under pressure is supplied by a suitable fuel supply pump (not shown). The inlet ports 42 and 44 communicate respectively with the fuel supply passages 46 and 48 which in turn open into the fuel distribution chamber 22. The pressurized fuel passes through the passages 46 and 48 into the fuel distribution chamber when the plunger exposes the passages to the chamber and is pumped sequentially to the cylinders of the engine by the upward strokes of the plunger, the fuel in the chamber being forced through fuel delivery check valve 50 as shown in FIG. 2. Fuel flowing through the check valve passes around the valve plunger 52 and through passages 54 and 56 in the plug 58 to an annulus 60 in the plug. The fuel flows from the annulus 60 through passage 62 in the pump head into the annulus 64 of the plunger and then into the plunger groove 66, which sequentially communicates with spaced distributor passages 68 in the pump head during rotation of the plunger. Each distributor passage 68 communicates with an outlet passage 70 from which fuel is discharged through outlet ports 72 to the cylinders of the engine, the cylinders being connected thereto by means of suitable tubing. The number of ports 72 corresponds, of course, with the number of cylinders in the engine, the present pump having six ports and thus being adapted to provide fuel for a six cylinder engine. The rotation of the plunger is timed to sequentially position the plunger groove 66 in alignment with the distributor passages for delivery of fuel to the cylinders in the proper phase relation to the engine cycle.

The amount of fuel delivered by the pump is regulated by the position of the control sleeve 74 slidably located on the plunger in the sump 24 in a manner to be presently described. The control sleeve 74 is vertically positioned on the plunger within the sump 24 by means of a conventional stub shaft and eccentric pin connected with the control rod linkage from the governor, none of which is shown in the present drawings in view of its completely conventional character. The plunger includes an axial bore 76 which extends from the upper end of the plunger to the radial spill ports 78 communicating with the sump 24. When the spill ports 78 are covered by the control sleeve 74, fuel cannot pass from the fuel distribution chamber through bore 76 to the sump. However, when the spill ports clear the sleeve toward the end of the plunger pumping stroke, the pressure in the distribution chamber is reduced to the sump pressure, permitting the check valve 52 to close and stopping further fuel delivery. By adjustment of the vertical sleeve position, the duration of the pumping action and hence the amount of fuel delivered may be accurately controlled.

A pair of downwardly inclined fuel conduits 80 and 82 extend from the fuel inlet ports 42 and 44, connecting the inlet ports with an annular head sump 84 which is con-

nected with the sump 24 by a port (not shown) to provide the fuel supply pressure in the sump 24.

The fuel injection pump structure and operation as described so far are conventional and are in most respects similar to that of the above-mentioned U.S. Patent 2,518,473. It can be understood from the above description that during the return or suction stroke of the plunger, a period exists during which both the spill ports 78 and the fuel supply passages 46 and 48 are respectively closed by the control sleeve and the plunger. This period is prolonged when the control sleeve is set at an elevated position in the sump such as at maximum fuel delivery. In order to prevent a vacuum condition in the fuel distribution chamber during this period and consequent cavitation erosion of the chamber and fuel passages, and further to insure the filling of the fuel distribution chamber over a full range of engine speeds with a normal fuel supply pressure, a supplementary fuel distribution chamber filling means is provided as described below. As will be noted from the description of the filling means, this arrangement also serves to prevent reverse operation of the engine and the serious damage to the engine which can result therefrom.

The supplemental filling means comprises a plurality of radial supplemental ports in the plunger communicating with the plunger bore 76 and located below the plunger annulus 64 but above the sump 24. The supplemental plunger ports in the present embodiment comprise three upper ports 86 radiating at 120° angles from the plunger bore and three lower ports 88 in closely spaced relation therbelow similarly radiating from the plunger bore at 120° angles in staggered relation to the ports 86, there thus being a port radiating from the plunger bore at each 60° of the plunger circumference as illustrated in FIGS. 4, 6 and 8.

Complementing the plunger ports 86 and 88 are a plurality of supplemental conduits 90 connecting the hydraulic head bore 16 with the annular head sump 84. The supplemental conduits 90 are six in number and are spaced at exactly 60° intervals so as to complement the six plunger ports 86 and 88 during operation of the pump in a manner to be described below. The point of connection with the conduits 90 with the plunger bore 16 is such that the upper row of plunger ports 86 are horizontally aligned for communication with the conduits at bottom dead center as shown in FIGS. 1 and 3 while the lower plunger ports 88 are horizontally aligned for communication with the conduits at top dead center as shown in FIG. 5. The importance of the proper circumferential location of the conduits 90 with respect to the plunger ports 86 and 88 will be apparent from the following description of the operation of the supplemental filling means.

Referring to the graph of FIG. 9, with the cam-shaft 26 rotating at one-half engine speed, a full cycle of the injection pump will occur every 120° of engine crank-shaft rotation using the six lobe cam 28. On the upstroke or pumping stroke of the plunger, the plunger covers the fuel supply passages 46 and 48 at point A on the graph, at which point compression and pumping of the fuel in the fuel distribution chamber by way of the check valve 52 and connected passages begins as described above. Pumping of the fuel continues until the spill ports 78 of the plunger rise above the control sleeve 74 at a given setting of the control sleeve which may for example be at point B on the graph. Since fuel from the fuel distribution chamber may now escape through the bore 76 of the plunger and through spill ports 78 into the sump 24, compression of the fuel in the fuel distribution chamber stops at point B and the check valve 52 closes.

As the plunger reaches point C at top dead center, the spill ports 78 are still in communication with the sump and remain in communication therewith until point D on the graph is reached, at which point the spill ports return within the control sleeve which cuts off communication with the sump. Since the plunger does not uncover the fuel supply passages 46 and 48 until point E on the graph

has been reached, in the absence of the supplemental filling means of the present invention, it can be understood that from point D to point E on the graph there would be a period of rapidly decreasing pressure within the fuel distribution chamber during which period fuel vaporization and the resultant cavitation on breaking of the vacuum condition occurs. Prior to the present invention, it can be understood that the filling of the fuel distribution chamber took place only from points C to D following by the described interruption, and then from point E through point F at bottom dead center back to point A while the fuel supply passages are exposed.

With the present supplemental filling means, as shown in FIGS. 5 and 6, at top dead center, represented by point C on the graph, the spill ports 78 are in communication with the sump 24 and, at the same time, the supplemental ports 88 are just beginning to rotate into communication with the supplemental conduits 90, adding a further source of fuel input to the fuel distribution chamber, the fuel entering from the annular head sump 84 through the conduits 90, ports 88, and the bore 76 of the plunger into the fuel distribution chamber.

Midway through the downstroke or suction stroke of the plunger, as shown in FIGS. 7 and 8, the supplemental ports 88 and 86 have rotated into radial alignment with the supplemental conduits 90 and the downward movement of the plunger has brought both rows of supplemental ports into communication with the conduits. At this point, the fuel supply passages 46 and 48 have still not been uncovered by the downward plunger movement although, and as can be seen from FIG. 7, the spill ports 78 are within the control sleeve 74 so that the supplemental ports and conduits are at this point providing the only source of fuel input to the fuel distribution chamber.

At the bottom dead center plunger position shown in FIGS. 3 and 4, the supplemental ports 86 are horizontally aligned with the conduits 90 as shown in FIG. 3 but are just being rotated out of phase with the conduits as shown in FIG. 4 to prevent further fluid communication therewith. It can thus be seen that the supplemental ports and conduits provide a supplemental fuel input to the fuel distribution chamber through out the entire downstroke or suction stroke of the plunger from the point C to point F on the graph of FIG. 9.

By supplementing the interrupted fuel input heretofore provided only by the spill ports from point C to point D and by the fuel supply passages 46 and 48 from point E through point A, the present supplemental filling means can be understood to provide a greatly improved filling efficiency of the pump. The supplemental filling effect is, of course, in addition to the conventional filling arrangement so that filling of the fuel distribution chamber continues from point B when the spill ports 78 open through the remainder of the upstroke, the entire downstroke, and the beginning of the subsequent upstroke to point A at which point the fuel supply passages 46 and 48 are closed. Fuel is thus continuously supplied to the fuel distribution chamber during the plunger cycle except from point A to point B during compression and injection of the fuel.

The supplemental conduits 90 and complementing supplemental ports 86 and 88 serve a further important function in preventing the reverse operation of the engine. Should the engine start to rotate in a reverse direction such as following a false start, the pump being coupled to the engine will also rotate in a reverse direction and the pumping stroke of the plunger as represented on the graph of FIG. 9 will now extend to the left from point F to point C, which is the portion of the cycle during which the supplemental ports 86 and 88 remain in continuous communication with the conduits 90. Upward movement of the plunger during a reverse rotation of the pump cannot compress the fuel in the fuel distribution

chamber since communication of the chamber with the head sump 84 is continuously provided by the supplemental ports and conduits throughout the reverse pumping stroke of the plunger. The check valve 52 is thus never open during reverse operation of the pump and no fuel is injected into the engine, effectively preventing reverse engine operation.

The number of supplemental conduits and supplemental ports is conveniently chosen to coincide with the number of outlet ports 72 in the pump. In the present instance, with a six cylinder engine, there are accordingly six conduits and six complementing plunger ports. A similar system could, of course, be provided for a four or an eight cylinder engine with the same principles being utilized to provide a supplemental fuel distribution chamber filling means.

From the foregoing it can be understood that the invention presented carries out all of the foregoing objects in providing a supplemental filling means for a distributor type injection pump which insures an efficient pump filling even under high speed engine operation with normal fuel supply pressures (15-60 p.s.i.). Cavitation erosion is significantly reduced by the present invention and reverse engine operation is effectively prevented.

Manifestly, changes in details of construction can be effected by those skilled in the art without departing from the spirit and the scope of the invention as defined in and limited solely by the appended claims.

I claim:

1. In a fuel injection pump including a hydraulic head having a bore therein, a plunger rotatably and slidably disposed within the bore, the bore end above the plunger comprising a fuel distribution chamber, a first sump spaced from the chamber surrounding the plunger, an annular second sump radially spaced from and interconnected with said first sump, fuel supply means for delivering fuel to the fuel distribution chamber and to said sumps, said fuel supply means including at least one fuel supply passage in said hydraulic head bore opening directly into said fuel distribution chamber during a portion of the plunger cycle, fuel delivery means operable to deliver fuel sequentially from the fuel distribution chamber to cylinders of an engine in a predetermined order during compression strokes of the plunger, passage means in the plunger connecting the fuel distribution chamber and said first sump, and an adjustable control sleeve slidably mounted on the plunger in said first sump which may be selectively positioned to control the opening of said passage means in the plunger during the plunger compression stroke to control the amount of fuel discharged from the fuel distribution chamber to the engine, the improvement comprising supplemental filling means for providing a supplemental fuel filling of said fuel distribution chamber during the entire suction stroke of said plunger, said supplemental filling means comprising at least one supplemental port in said plunger extending radially from said plunger passage means and at least one complementing supplemental conduit in said hydraulic head adapted to provide fluid communication between said annular second sump and said supplemental plunger port during the entire suction stroke of said plunger, said supplemental port being phased out of communication with said supplemental conduit during the compression stroke of the plunger by the plunger rotation.
2. The improvement as claimed in claim 1 wherein said supplemental port is in communication with said supplemental conduit throughout the suction stroke of said plunger.
3. The improvement as claimed in claim 1 wherein said supplemental ports and conduits are disposed between said fuel distribution chamber and said first sump.
4. The improvement as claimed in claim 1 wherein said supplemental filling means comprises an equal number of supplemental ports and supplemental conduits.

5. The improvement as claimed in claim 4 wherein said supplementary filling means comprises a number of supplementary ports and supplementary conduits corresponding to the number of outlet ports of the pump.
